CONTAINER AND PICTURE HOLDER

Eric Anderson, Providence, R. I., assignor to
Superb Case Mfg. Co., Providence, R. I., a corporation of Rhode Island

Application November 8, 1940, Serial No. 364,831

3 Claims. (Cl. 40—156)

My present invention relates to cigarette cases, vanity cases and the like, and has particular reference to a novel construction of cover therefor.

The principal object of the present invention is to provide a case or container in which the inside of the cover portion forms a combination mirror and retainer for photographs or the like.

A further object of the present invention is to provide a container of the type specified, which is simple in construction and easy and economical to manufacture and assemble.

Another object of the present invention is to provide a container in which the inside cover portion provides a combination mirror and photograph or other article holder which is open to view upon the opening of the container.

With the above and other objects and advantageous features in view, my invention consists of a novel arrangement of parts more fully disclosed in the detailed description following and more particularly defined in the claims appended thereto.

In the drawing:

Fig. 1 is a perspective view of a container embodying my invention, in open position;

Fig. 2 is a plan view of the lock frame;

Fig. 3 is a plan view of the combined mirror and photograph retainer;

Fig. 4 is a section taken on line 4—4 on Fig. 1;

Fig. 5 is a perspective view of one of the transparent covers; and

Fig. 6 is a fragmentary detail view of the lock arrangement.

Cigarette cases, powder compacts, vanity cases and the like are often provided with mirrors on the inside of the cover portion for the convenience of the user. The present invention is designed to provide a cover construction for this type of container which includes a provision for retaining photographs or other indicia without impairing the utility of the mirror. For the purposes of illustration only, the present invention is shown and described as embodied in a cigarette case. However, the invention may readily be applied to compacts, vanity cases, and similar containers.

Referring more in detail to the drawing embodying my invention, the container 10 includes a base 11 and a cover 12 hinged thereto as at 13. The hinging 13 may be of the conventional spring type for opening the cover portion when the latch 14 in the base 11 is depressed. As shown in Fig. 1, the base 11 holds cigarettes 15 which are retained in the case by the spring-pressed arm 16 in the conventional manner.

The inside of the cover 12 is provided with a combined mirror and retainer member 17 illustrated in Figs. 1 and 3. The member 17 is preferably of an integral construction and stamped from sheet stock, the visible surface being highly polished. Any mirror-surfaced metal may be used, such as "Monel" metal, which will give a highly polished reflecting surface. The member 17 is of the same shape as the cover 12 (rectangularly shown) and is provided at its lower portion with one or more pockets or retainer portions 18 which may be stamped therefrom in any desired shape. The pockets 18 are preferably stamped from the surface of the member 17 so as to provide front wall portions 19 which extend laterally from the surface of the member 17 in a V shape, the upper edge 20 forming a comparatively wide opening and the side walls of the pocket tapering downwardly towards the lower end 21 until the front surface merges with the surface of the member 17. The front of the portion 18 may be cut out, as at 22, so that the article in the pocket may be visible, and the member 17 may be cut away, as at 23, adjacent the upper end 20 of the pocket so that a finger can be inserted to remove any article from the pocket. A transparent window insert 24, illustrated in Fig. 5, may be slipped into the pocket portion 18 so that the photograph or other item interposed in the pocket may be separated from the contents of the container and be prevented from becoming soiled or discolored.

The member 17 is locked in the cover portion 12 by a lock frame 25, illustrated in Fig. 2. The lock frame 25 comprises a narrow integral rectangular frame portion adapted to snugly fit the interior of the cover 12 and provided with an integral upstanding flange 26 around the outer edges thereof. The sides of the cover portion 12 are provided with a plurality of detents 27, see Fig. 6, spaced from the inside cover surface and having generally rounded upper portions and flat lock shoulders on the underside thereof.

In assembling, the member 17 is positioned in the cover 12, as shown in Fig. 1, and the lock frame 25 is pushed down over it into the positions shown in Figs. 1 and 6, the flange 26 snapping under the detents 27 and securely locking both the lock member 25 and member 17 to the cover. The use of the flange 26 on the frame 25 permits a minimum number of detents 27 to be used, it being preferred to utilize two at each corner of the cover, and gives the frame rigidity. This provides a firm locking and prevents rattling or sliding of the parts.

The above-described construction thus provides a container for cigarette cases, vanity cases, and similar articles in which the inside cover is provided with a mirror and pocket portion in which photographs, social security numbers or the like may be easily inserted and retained in a clearly visible position. In view of the tapered form of the pocket 18, the photograph or other indicia slips into the pocket between the under surface of the cover and the window member 24 becomes 10 wedged into the lower end 21 of the pocket between the member 17 and the underside of the cover, so that it will not slide from the pocket nor become displaced in any position of the container and can only be removed by a positive manual action. The pocket is thus self locking and retains insertions therein without the use of additional locking devices.

While I have described a constructional embodiment of my invention, it is obvious that changes may be made in the size and shape of the parts, in the number of pockets used, in their relative shape, and in the size and arrangement of the mirror member, without departing from the spirit and the scope of the invention 25 as defined in the appended claims.

I claim:

1. A container comprising a base, a cover hingedly connected to said base, and a mirror and retainer member locked to the inside of said cover, said member comprising a sheet metal plate having a mirror surface on at least one side and an integral pocket portion extending outwardly from said mirror surface.

2. A container comprising a base, a cover hingedly connected to said base, and a mirror and retainer member locked to the inside of said cover, said member comprising a sheet metal plate having a mirror surface on at least one side and an integral pocket portion extending outwardly from said mirror surface in a V shape.

3. A container comprising a base, a cover hingedly connected to said base, and a mirror and retainer member locked to the inside of said cover, said member comprising a sheet metal plate having a mirror surface on at least one side and an integral pocket portion extending outwardly from said mirror surface, the front of said pocket portion having an opening.

ERIC ANDERSON.
